UNITED STATES PATENT OFFICE.

FREDERICK S. STRONG, OF EAST BRIDGEWATER, MASSACHUSETTS, AS
SIGNOR TO THE CARVER COTTON GIN COMPANY, OF SAME PLACE.

SHOE-HOLDING JACK.

SPECIFICATION forming part of Letters Patent No. 282,128, dated July 31, 1883.

Application filed June 14, 1883. (No model.)

To all whom it may concern:

Be it known that I, FREDERICK S. STRONG, a citizen of the United States, residing at East Bridgewater, in the county of Plymouth and State of Massachusetts, have invented 5 certain new and useful Improvements in Shoe-Holding Jacks, of which the following is a specification.

My invention relates to certain improvements in that class of swinging jacks which are used in shoe-sole-leveling machines, the object being to improve the several adjusting devices by which the jack is adapted to the size of the last and to the inclination of the 15 hole that is bored in the last for receiving the heel-pin, so that the sole of the shoe may be presented to the action of the roller in a line as nearly as possible with the rectilinear motion of the roller. I attain these objects by 20 the mechanism illustrated in the accompanying drawings, in which—

Figure 1 is an elevation of my improved jack. Fig. 2 is a plan of the same. Fig. 3 is a horizontal section taken on line $y-y$, Fig. 1. 25 Fig. 4 is a cross vertical section on line $x-x$.

A A', Figs. 1 and 2, represent the frame of the leveling-machine. At the upper end of these parts A A', I pivot the swinging jack-frame B B'. This jack-frame has in its lower 30 portion a curved housing, B⁴, in which the jack-pillar C may slide in a curvilinear direction to a limited degree. In striking the curve for the curved housing B⁴, I use as a center a point at P, Fig. 1, which is very near 35 the plane of the lower part of the last as the last sits upon the jack. This point I have found by experience gives a curve to the housing B⁴, which on an average is best adapted to all sizes of shoes, and it gives the least amount 40 of tilting to the forward part of the last. Hence by using this point as a center I am enabled to jack all sizes and to maintain the level of the sole approximately in a horizontal plane, this being a great advantage in the 45 practical working of the machine. The jack-pillar C is fastened in its position in the housing B⁴ by means of the clamping-bolts D D'. (See Figs. 1, 2, and 3.) The part C' of the 50 jack-pillar is cylindrical, and has within it a vertical moving piston, C³, into which is inserted the heel-pin C⁴. The lower end of the piston C³ terminates in a screw, C⁵, Fig. 4. This screw C⁵ passes through a revolving nut,

E, Figs. 3 and 4, the nut E being held from any vertical movement, so that when it is revolved the piston C³, and consequently the heel-pin C⁴, must move up and down, thus giving it the vertical adjustment I require. The outer surface of the nut E is a gear, E', as shown in Fig. 3, which meshes with the worm-gear E² on the shaft E³, the whole being operated by the hand-wheel E⁴.

The toe-support-adjusting device consists of a sliding piece, H, (see Figs. 1 and 2,) which slides horizontally, as shown in Fig. 1, and is held in any desired position by the clamping-bolt H', which passes through a slot made in the part H, and indicated by dotted lines at H², Fig. 1. In addition to the horizontal adjustment of the toe-support I have an inclined 70 adjustment which is made as follows: The toe-support proper, K, is made forked shape, and is fitted to slide upon the upper inclined part of the sliding piece H. This support K can be moved back and forth to any desired position on the piece H, and there held by the set-screw K'. To change the angle of the heel-pin C⁴, I slack the clamping-screws D D' and slide the jack-pillar C and all its parts back or forth, as may be desirable, in the housing 80 B⁴. In case I slide it to the left, the pin C⁴ will approach the perpendicular. If I slide it to the right, the pin will be more inclined. When the right position has been attained, the clamping-bolts D D' are screwed up. 85

I claim as my invention—

1. In a swinging jack, the combination of the heel-pin C⁴, piston C³, pillar-jack C C', mounted upon a curved housing, B⁴, and screw C⁵, with the screw-nut E, and worm-gear E' E², shaft E³, and hand-wheel E⁴, all operating together substantially as described, and for the purpose set forth.

2. In a jack, the combination of the adjustable toe-support K, adapted to slide upon the inclined upper part of the sliding piece H, and sliding piece H, with the frame B B', said sliding piece H being adapted to move horizontally on the said jack-frame B B', and to be clamped in position by a screw, H', all 90 operating together substantially as described, and for the purpose set forth.

FREDERICK S. STRONG.
